C. J. COOKE.

NON-RECOIL GUN.

APPLICATION FILED MAR. 24, 1920.

1,380,358.

Patented June 7, 1921.

UNITED STATES PATENT OFFICE.

CHARLES J. COOKE, OF WASHINGTON, DISTRICT OF COLUMBIA.

NON-RECOIL GUN.

1,380,358.

Specification of Letters Patent. Patented June 7, 1921.

Application filed March 24, 1920. Serial No. 368,438.

To all whom it may concern:

Be it known that I, CHARLES JOHN COOKE, a subject of the King of the United Kingdom of Great Britain and Ireland, and a 5 resident of the city of Washington, District of Columbia, U. S. A., have invented certain new and useful Improvements in Non-Recoil Guns; and I do hereby declare the following to be a full, clear, and exact description of the invention, such as will enable others skilled in the art to which it 10 pertains to make and use the same.

My present invention relates to ordnance but more particularly to guns of the non-recoil type, open at both ends, adapted to 15 fire a suitable shell or projectile in one direction, and to utilize the escaping gases of combustion to counterbalance the recoil, as exemplified by disclosures contained in my 20 pending application Serial Number 270,610.

It has for its chief object the production of portable guns of the class described, either of large or small caliber, and of comparatively light weight, capable of being 25 operated from more or less fragile mounts, such for example as aeroplanes, seaplanes, and light gun-carriages which could not withstand the recoil forces of ordinary guns.

A further object of the present invention 30 is the production of non-recoil guns characterized by a diverging deflector at the rear end in direct communication with the firing chamber of the gun, the same being designed, arranged and adapted to utilize 35 the expansion of the gases as they pass through said diverging deflector for the purpose of dissipating the recoil forces resulting from the explosion in ordinary guns.

A further object is the employment of 40 additional muzzle defectors at the forward end of guns of the class indicated, so positioned and arranged with relation to the gun barrel that escaping gases, following the flight of a projectile, will impinge upon 45 said forward deflectors to assist in counter-acting the recoil forces.

A further object of the invention is the production of non-recoil guns of comparatively light and durable construction, consisting essentially of a unitary gun barrel 50 and rearwardly diverging deflector elements capable of counteracting recoil of the gun by agency of expanding gases as they pass rearwardly through said diverging deflector.

With the foregoing and other objects in view, as also certain novel details of con-

struction by which such objects are facilitated, the present invention will now be particularly described, and hereinafter pointed out by the appended claims.

60

In the accompanying drawings which form part of this application for Letters Patent, and whereon like numerals refer to corresponding parts in the several views:

65

Figure 1 is a longitudinal central sectional view of the invention, suspended by parallel links from the fuselage of an aeroplane in parallelism with the longitudinal axis thereof; and

Fig. 2 is a transverse sectional view 70 through the breech of gun, taken on the line 2—2 of Fig. 1.

Reference being had to the drawings illustrating one embodiment of the present invention, and to the numerals thereon, 1 indicates a gun barrel of any suitable material or known form of construction, preference being given to those materials commonly employed in the construction of heavy ordnance, such for example as high 75 grade alloyed steel because of its inherent strength and comparative lightness.

Extending rearwardly from the gun barrel or body 1, and in direct communication with the interior thereof, is an outwardly 80 diverging tubular deflector 2 of comparatively light weight.

As shown in its simplest form of construction, the said tubular and diverging deflector 2 may be forged or otherwise formed integral with the gun body 1 at its breech, and with walls of outwardly tapering thickness, although it should be understood that the last mentioned feature is by no means 90 essential, and the said diverging deflector 2 95 may readily be formed as an independent detachable member if desired.

At its opposite or forward end the gun barrel 1 is surrounded by an exterior screw threaded collar 3 to which is securely bolted a series of forward muzzle deflectors 4, each consisting of an annulus having a central opening 5 of slightly greater diameter than the central bore 6 of the gun and each cupped upon its rear face as shown, the several deflectors being spaced apart by sleeves or space blocks 7 surrounding the bolts 8 by which they are held securely in place.

Projecting laterally from sides of the gun body 1, are forward and rear trunnions 9, 9, 9, 9, in oppositely disposed pairs, by means of which the gun may be mounted. The

105

110

present illustrations show the gun suspended beneath and parallel with the longitudinal axis of the fuselage of an aeroplane, at the end of depending links 10, 10 and 11, 11.

- 5 The said links all hang vertically from and are pivotally connected as at 12 and 13, to the bottom 14 of an aeroplane; or, for convenience of loading the gun, the forward pair 10, 10, of said links may be pivotally connected as shown at 12 to the underside of a trap door 15 opening into the cockpit of the fuselage. Obviously when this door 15 is raised inwardly upon its hinges 16, the gun, pivoting upon the lower extremities 15 of links 11, enters the cockpit of the fuselage at its outer end in convenient position for loading.

Preferably fixed ammunition is employed in obtaining the best results from the present invention, consisting, as shown by Fig. 1, of a slug or projectile 17, fitted with screw trailing blades 18, having an open center as shown and embedded in the firing cartridge or propelling charge 19, and surrounded by 25 a cartridge case 20 of relatively stiff nitro-cellulose or other combustible material. Within said cartridge case also, at its extreme rear center, is provided a wad 21 for bridging the communicating opening between the rear end of gun body 1 and the front end of its diverging deflector tube 2 for purposes which will later appear.

When dropped into the mouth of the gun the charge assumes the position indicated by 35 Fig. 1, with its frangible wad 21 temporarily closing the rear end of gun, and its annular depression or groove 22 engaged by the protruding end of spring latch or plug 23 to retain the fixed charge in proper firing 40 position. The actual firing may be accomplished by various means both mechanical and electrical, as for example by agency of a detonating fuse or fuses 24 embedded centrally in the cartridge and provided with an 45 electric lead 25, which may extend rearwardly through deflector 2, to a suitable circuit closing switch (not shown), or said firing wires may lead into the cartridge and to a suitable switch-controlled electric circuit (not shown) by way of the aforesaid 50 spring-pressed electric firing pin and latch 23, passing through and insulated from the hollow nipple 26 screwed into the gun barrel substantially as shown.

55 At both sides the depending gun-supporting links 11 are yieldingly connected to the bottom 14 of the fuselage by interposed tension springs 27, 27, arranged and adapted to yield slightly at the instant of firing, but 60 under normal conditions to maintain the gun in proper firing position.

In suspending a gun thus from the bottom 14 of the fuselage of an aeroplane, it will be noted that its firing position is always in 65 parallelism with the longitudinal axis of

said fuselage thereby making it possible to train the gun upon a given target by the simple process of aiming the aeroplane at it. It will be particularly noted also that said depending and parallel arrangement insures 70 the greatest possible degree of safety to both aeroplane and its operators from the possibility of fire and burning gases following a discharge of the gun.

The foregoing being a description of my 75 present invention in its simplest and best form of embodiment at present known to me, its use and operation will now be briefly set forth as follows:

Presuming that a fixed ammunition 80 charge is employed and that same is positioned as shown by Fig. 1 in the firing chamber of the gun 1, also that a suitable firing fuse or fuses 24 are embedded in the propelling charge 19, and suitably connected 85 with a switch-controlled electric circuit operating through nipple 26 or otherwise as a firing means, it will be noted that under such conditions closing of said electric circuit in the well understood manner now 90 serves to fire fuses 24 which in turn ignite the charge 19. The combustible cartridge case 20 is promptly consumed, and the gases of combustion instantly drive the shot or shell 17 forward with great muzzle velocity, 95 at the same time forcing the frangible wad 21 through the constricted opening which it had served to temporarily bridge. The momentary obstruction of the constricted front opening of the deflector 2, by the frangible 100 wad 21 causes the pressure of the propelling gases to rise rapidly. The wad 21 is now blown through the said constricted opening, but the pressure of the gases in the meantime having reached a high value, combustion 105 continues at a sufficient velocity to be effective.

While the projectile 17 is moving through the barrel of the gun a recoil of the entire gun is initiated, the amount of this recoil 110 being very much less than that of an ordinary gun, due to the forward reaction produced by the expanding gases in their action upon the interior diverging walls of deflector 2, while at the same time gases following 115 the shot 17 in its flight immediately after leaving the gun, impinge directly upon the cupped muzzle deflectors 4 for the same purpose of absorbing the recoil.

When in flight it is quite obvious that the 120 trailing blades 18 impart to the shot 17 a rotary movement even though fired from a gun of smooth bore as shown in the present illustrations, and because of the skeleton form or open center construction as shown 125 by Fig. 2, of said blades 18 the propelling charge 19 is ignited as a unit.

After a shot has been fired as aforesaid the reloading may be conveniently, expeditiously and safely effected by lifting trap 130

door 15 upon its hinges 16. By agency of connecting links 10, 10, the outer extremity of the gun is thus elevated, as indicated by the dot and dash line of Fig. 1, into the 5 cockpit of an aeroplane or similar vehicle, at an angle which makes it possible to introduce a fixed charge and quickly seat same by gravity in operative position.

While the foregoing is a description of 10 my invention in the best form of construction at present known to me, it should be understood that I by no means limit myself to the coördinating arrangement and combination of parts shown and described. On 15 the contrary such arrangement and combination may be varied greatly without in the least departing from the spirit of my invention, or the broad terms of the claims by which it is expressed.

Having thus described my invention, what 20 I now claim and desire to secure by Letters Patent is:—

1. A non-recoil gun comprising in combination a gun body and a rearwardly diverging deflector in direct communication with the interior of said gun body.

2. A non-recoil gun comprising in combination a gun body and a rearwardly diverging tubular deflector in direct communication with the interior of said gun body.

3. A non-recoil gun comprising in combination a gun body and a rearwardly diverging deflector communicating with the interior of said gun body by means of a constricted passage.

4. A non-recoil gun comprising in combination a gun body, a rearwardly diverging deflector communicating with the interior of said gun body by means of a constricted passage and a frangible wad for temporarily 40 closing said passage.

5. The combination with an aeroplane and an aeroplane gun, of means for pivotally suspending said gun beneath the fuselage of the aeroplane, and for maintaining 45 the gun always in parallelism with the longitudinal axis of the fuselage when in operative position.

6. The combination with an aeroplane and an aeroplane gun, of suitable links pivotally 50 connected to both aeroplane and gun for maintaining the latter below and always in parallelism with the longitudinal axis of the aeroplane when in operative position.

7. The combination with an aeroplane and 55 an aeroplane gun, of links pivotally suspending said gun beneath the fuselage of an aeroplane for maintaining the gun always in parallelism with the longitudinal axis of the fuselage when in operative position, and 60 tension springs connected to one of said links for returning same to its normal position.

In testimony whereof I affix my signature, in presence of two subscribing witnesses.

CHARLES J. COOKE.
